UNITED STATES PATENT OFFICE.

STANLEY GERON, OF YORKVILLE, NEW YORK.

FIRE-ALARM.

1,382,185.

Specification of Letters Patent. Patented June 21, 1921.

Application filed April 17, 1920. Serial No. 374,590.

To all whom it may concern:

Be it known that I, STANLEY GERON, a citizen of Poland, residing at Yorkville, county of Oneida, and State of New York, have invented certain new and useful Improvements in Fire-Alarms, of which the following is a specification.

This invention relates to automatic fire alarms, and more particularly to a fire alarm operating by thermostatic action and it has for an object to provide a novel and inexpensive form of thermostatic fire alarm whereby warning may be given in the event of a fire starting.

For further comprehension of the invention, and of the objects and advantages thereof, reference will be had to the following description and accompanying drawings, and to the appended claims in which the various novel features of the invention are more particularly set forth.

Figure 1 of the drawings is a side view of a thermostatic alarm constructed according to the invention.

Fig. 2 is a front view thereof.

Fig. 3 is a horizontal section on the line 3—3 of Fig. 2.

In practical use my improved alarm is mounted on the upper end of a pipe such as 30 10, connected to a source of water supply, the device comprising briefly, a fusible member closing the upper end of the pipe and a head arranged above the pipe and carrying two electrical contacts adapted to be closed 35 by the water discharged from the pipe when the fusible member melts.

As here shown the fusible member comprises a ball 11 of wax or other like material which is seated on the upper end of the pipe 40 and is pressed firmly thereon by a cap 12 screwed down over the pipe, this cap having a central nozzle orifice 13 in its top.

The head above referred to is shown at 15 and is here of cylindrical shape and made of insulating material and is arranged in axial alinement with the pipe 10. This head is 45 preferably supported between the upper ends of a pair of curved tubes 16 to which it is secured by an encircling band 17, these tubes being secured at their lower ends to the pipe 10 just under the cap 12 by another band 18.

This head 15 is formed with a circular recess 20 extending upwardly from its underside, in the top of which is mounted an inverted cup-shaped contact member 21 of

copper or other suitable material connected to a post 22 which extends upwardly through the head and has the end of a wire 23 connected thereto. Coöperating with the contact member 21 is a second contact member in the form of a short tube 24 extending upwardly into the cup 21 but spaced therefrom at all points, this tube having a flared or funnel-like lower end 24', and being in axial alinement with the pipe 10 so as to receive the jet of water discharged through the nozzle 13 when the fusible ball 11 melts. This second contact member is secured to the underside of the head 15 by means of an integral ear 25 formed on one side of the flared lower end thereof and clamped on the under side of the head by a screw 26, this screw also serving to secure the end of a second wire 27 to the ear 25. These wires 23 and 27 65 preferably lead downwardly through the tubes 16, the wire 23 leading through the open upper end of the adjacent tube, while the other tube has an opening, indicated at 28, in the side wall thereof to receive the wire 27. These wires 23 and 27 lead, as will 70 be understood, to an electric bell or other desired alarm.

Upon the occurrence of a fire in the vicinity of the device the rising of the temperature will cause the ball 11 to melt and the water to be discharged through the nozzle 13 into the tube contact 24 and upwardly against the other contact 21, the stream of water forming a bridging member which causes the circuit to be closed and the alarm to be sounded. It will be understood of course that these devices may be located wherever desired in buildings, ships or wherever there is danger of damage by fire. 85 90 95

Having thus described my invention what I claim as new and desire to secure by Letters Patent of the United States is—

1. A device of the class described comprising, a fusible member adapted to close the upper end of a pipe connected to a source of water supply, a cap having a nozzle orifice adapted to hold said fusible member in position closing said pipe, a head adapted to be supported above said cap, a pair of normally spaced contact members on said head, adapted to close an alarm circuit when impinged upon by the water discharged from the said nozzle orifice.

2. In combination with a pipe connected to a source of water supply, a fusible element closing the end of said pipe, a cap secured on

the pipe holding said element in position, said cap having a nozzle orifice, a head of insulating material supported in alinement with the said pipe, and a pair of fixed contact members carried by said head spaced from one another and adapted to be bridged by the stream of water flowing from said nozzle orifice.

3. In combination with a pipe connected 10 to a source of water supply, a fusible element closing the end of said pipe, a cap secured on the pipe holding said element in position, said cap having a nozzle orifice, a head of insulating material supported in 15 alinement with the said pipe, and a pair of fixed contact members carried by said head spaced from one another and adapted to be bridged by the stream of water flowing from said nozzle orifice, one of said contact members being of tube-like formation with a 20 flaring end.

4. In combination with a pipe connected to a source of water supply, a fusible ball

closing the end of said pipe, a cap screwed upon the end of the pipe inclosing said ball 25 and holding it in position on the pipe, said cap having a nozzle orifice, a cylindrical head of insulating material, a pair of tubes supported at their lower ends on said pipe and supporting said head on their upper 30 ends, said head having a cylindrical recess on its underside, an inverted cup-like contact member secured in said recess, a tubular contact member projecting upwardly into said cup and spaced from the walls thereof, 35 said tubular contact member having a flaring lower end, an ear on the lower end of said tubular contact member whereby it is secured to the head, and a post extending upwardly through the head from the first 40 contact member to secure the latter in position.

In testimony whereof I have affixed my signature.

STANLEY GERON.
